Inventor

A. F. Morey

United States Patent Office.

A. F. MOREY, OF GREENBUSH, ILLINOIS.

Letters Patent No. 75,954, dated March 24, 1868.

IMPROVED BARREL-TRUCK.

The Schedule referred to in these Letters Patent and making part of the same.

TO ALL WHOM IT MAY CONCERN:

Be it known that I, A. F. MOREY, of Greenbush, in the county of Warren, and State of Illinois, have invented a new and useful machine for moving barrels from place to place in shipping, or in stores, warehouses, &c., called a Barrel-Truck; and I do hereby declare the following to be a full, clear, and exact description of the construction and operation of the same, reference being had to the annexed drawings, making a part of this specification, in which—

Figure 1 is a perspective view, and

Figure 2 a sectional view of one of the hooks or holders.

The nature of my invention consists in providing a truck of suitable shape for convenience in loading, and wheels for ease in moving, with suitable and convenient apparatus for holding barrels in position.

To enable others skilled in the art to make and use my invention, I proceed to the following fuller description.

Similar letters of reference refer to like parts.

The bars A A, fig. 1, represent the sides of a rectangular frame, provided with a handle, B, at the rear end, for convenience in using. The cross-pieces B B are for the purpose of staying and supporting the pieces A A. The side-pieces A A are curved and sharpened at the lower end, in order that they may be easily slid under the barrel, and are curved back at the upper end, for greater convenience in handling. The cross-piece B B, at the lower end of the frame, carries on each end, and inside of the frame-pieces A A, a wheel, z z. The cross-pieces B B are curved slightly, that the barrel may fit snugly when placed longitudinally, and the side-pieces A A are curved, in order that the barrel may fit when placed laterally on the truck.

C, fig. 1, represents a sliding knuckle on the side-pieces A A. These knuckles are adjustable by means of the holes P P P, the lever D and spring S, the lever also carrying and operating the bolt N, by means of which the knuckle is held firmly in position as the bolt enters the holes P P. The cross-piece S is pivoted in holes on the inner side of the knuckles C C. To this cross-piece are attached the hooks or holders W W, for holding the barrel when laterally on the truck. These hooks are extended back of the cross-piece S, and carry on their rear end the handle R, by means of which they are operated. The cross-piece S may be taken out of the slides C by way of the slots E, leading to their bearing-place, and the device, fig. 2, inserted instead, by using the extended ends of the cross-piece S, fig. 2, for journals. The cross-pieces S S in either hooking-attachment are held in position by means of the wedge K, which again is held firm by the pin H.

V V, fig. 2, represent the side-pieces of the hooking-attachment, used when barrels are laid longitudinally on the truck. The side-pieces V V are curved in a suitable manner to catch and hold securely to the chine of the barrel, and the cross-piece S is extended to form journals on the end, while the cross-piece R is used as a handle for operating.

The manner of operating is deemed sufficiently plain without particular description. By raising the upper end sufficient to throw the points l l on the floor, they may be easily inserted beneath a barrel; then, in case the barrel is longitudinal on the truck, the device, fig. 2, is used; and in case of handling barrels laterally on it, the other hooks are used. In either case the position of the hooks may be adjusted to any-sized barrel or kegs, by means of the slides C C. By throwing the truck up at the handle-end, the weight may be balanced and supported on the wheels z z, and easily moved from place to place.

What I claim as my invention, and desire to secure by Letters Patent, is—

1. The slides C, in combination with the truck-frame, containing holes P P P, constructed substantially as described and arranged, and for the purpose set forth.
2. The hooks V V and W W, constructed as described, and in combination with the slides C C and truck-frame A A, constructed substantially as described and for the purpose set forth.

A. F. MOREY.
